US0D1081751S

(12) **United States Design Patent** (10) Patent No.: **US D1,081,751 S**
(45) Date of Patent: ** Jul. 1, 2025

(54) **ELECTRONIC VIDEO MAGNIFIER**

(71) Applicant: **HANGZHOU DUKANG TECHNOLOGY CO., LTD.,**
Hangzhou (CN)

(72) Inventors: **Xiang Ying**, Hangzhou (CN); **Yu Xie**,
Hangzhou (CN)

(73) Assignee: **HANGZHOU DUKANG TECHNOLOGY CO., LTD.,**
Hangzhou (CN)

(**) Term: **15 Years**

(21) Appl. No.: **29/859,248**

(22) Filed: **Nov. 9, 2022**

(51) LOC (15) Cl. **16-06**

(52) U.S. Cl. **USPC D16/135**

(58) **Field of Classification Search**

USPC D6/309; D16/130, 134, 135, 136, 137
CPC G02B 25/002; G02B 25/02; G02B 25/004;
G02B 25/005; G02B 27/021

(57) **CLAIM**

The ornamental design for an electronic video magnifier as shown and described.

DESCRIPTION

FIG. 1 is a perspective view of an electronic video magnifier showing our new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof;

FIG. 7 is a bottom plan view thereof;

FIG. 8 is a view showing another position thereof;

FIG. 9 is a view showing another position thereof;

FIG. 10 is a view showing another position thereof;

FIG. 11 is a view showing another position thereof;

FIG. 12 is a view showing another position thereof;

FIG. 13 is a view showing another position thereof;

FIG. 14 is a view showing another position thereof; and,

FIG. 15 is a view showing another position thereof.

1 Claim, 15 Drawing Sheets
